CLAIM

The ornamental design for a drug package, as shown and described.

DESCRIPTION

The file of this patent contains atleast one drawing executed in color. Copies of this patent with color drawing(s) will be provided by the Office upon request and payment of the necessary fee.

FIG. 1 is a top, side perspective view of a first embodiment of a drug package;

FIG. 2 is a front view of a first embodiment of a drug package;

FIG. 3 is a top view of a first embodiment of a drug package;

FIG. 4 is a bottom view of a first embodiment of a drug package;

FIG. 5 is a top, side perspective view of a second embodiment of a drug package;

FIG. 6 is a front view of a second embodiment of a drug package;

FIG. 7 is a top view of a second embodiment of a drug package;

FIG. 8 is a bottom view of a second embodiment of a drug package;

FIG. 9 is a front top perspective view of a third embodiment of a drug package;

FIG. 10 is a front view of a third embodiment of a drug package;

FIG. 11 is a top view of a third embodiment of a drug package;

FIG. 12 is a bottom view of a third embodiment of a drug package;

FIG. 13 is a top, side perspective view of a fourth embodiment of a drug package;

FIG. 14 is a front view of a fourth embodiment of a drug package;

(Continued)

FIG. 15 is a top view of a fourth embodiment of a drug package;
 FIG. 16 is a bottom view of a fourth embodiment of a drug package;
 FIG. 17 is a top, side perspective view of a fifth embodiment of a drug package;
 FIG. 18 is a front view of a fifth embodiment of a drug package;
 FIG. 19 is a top view of a fifth embodiment of a drug package;
 FIG. 20 is a bottom view of a fifth embodiment of a drug package;
 FIG. 21 is a front top perspective view of a sixth embodiment of a drug package;
 FIG. 22 is a front view of a sixth embodiment of a drug package;
 FIG. 23 is a top view of sixth embodiment of a drug package; and,
 FIG. 24 is a bottom view of a sixth embodiment of a drug package.

The broken lines shown in the drawings are for the purpose of illustrating parts of the article that form no part of the claimed design.
